SEPARABLE SLIP

Samuel Katz, Bronx, N. Y.

Application April 14, 1949, Serial No. 87,389

9 Claims. (Cl. 2-70)

1

This invention relates to new and useful improvements in that general class of garments worn by women and misses and known as slips, and, more particularly, the aim is to provide a novel and valuable slip or the like, which is interchangeable at its bodice and skirt portions by such an easily and expeditiously effectuated type of interconnecting means for said two garment portions as a slide fastener; which at the same time may have the bodice portion incorporate a plain or embroidered brassière-like upper front formation; and which, further at the same time, is characterized by the inclusion of an elastic construction, partially included in the skirt portion and complementarily included in the bodice portion, for adding to the comfort of the wearer yet for drawing in the new garment, at a single point or zone interrupting the otherwise substantially inelastic circumference of the garment at and adjacent to the waist and hips engaging regions thereof, in a perfect form fitting manner, while nevertheless rendering the garment, without any opening up of such slide fastener, readily donnable as a pull over garment.

More specifically, the invention provides (in combination with a bodice portion and a skirt portion adapted to be substantially fully joined by said slide fastener and adapted to be wholly separated when desired by full opening of the slide fastener, a pair of elastic inserts, one at the back of the garment and carried at the bottom of the bodice portion and another also at the back of the garment and carried at the top of the skirt portion and in vertically centralized alignment with the said insert of the bodice portion) various improved features of construction at and adjacent to said inserts and the slide fastener.

Another object of the present invention proposes the provision of a novel means for releasably attaching together the adjacent edges of the elastic inserts in a manner to prevent a gap from forming between those adjacent edges when stooping over without interfering with normal stretching of those inserts.

It is a further object of the present invention to form an undergarment of the class referred to which is easy to manufacture, which can be sold at a reasonable cost and which will be effective for its intended purposes in use.

For further comprehension of the invention, and of the objects and advantages thereof, reference will be had to the following description and accompanying drawings, and to the appended claims in which the various novel features of the invention are more particularly set forth.

2

In the accompanying drawings forming a material part of this disclosure:

Fig. 1 is a rear elevational view of an undergarment constructed in accordance with the present invention and having applied thereto dot and dash lines for indicating various different positions of the parts of the garment under different conditions.

Fig. 2 is a rear perspective view of the garment as it will appear while being worn.

Fig. 3 is an enlarged detailed view of a portion of Fig. 1.

Fig. 4 is an enlarged partial vertical sectional view taken on the line 4-4 of Fig. 3.

Fig. 5 is a view similar to Fig. 3, but looking from the inside of the garment.

Fig. 6 is a diagrammatic view looking in the direction of the line 6-6 on Fig. 3 illustrating the circumferential extent of the slide fastener.

Fig. 7 is a rear elevational view similar to a portion of Fig. 1, but illustrating the undergarment constructed in accordance with a modification of the present invention.

Fig. 8 is a partial rear elevational view of the bodice portion used in the form of the invention shown in Fig. 7.

Fig. 9 is a partial rear elevational view of the skirt portion used in the form of the invention shown in Fig. 7.

Fig. 10 is an enlarged partial vertical sectional view taken on the line 10-10 of Fig. 7, but with the respective snap fastener elements in a separated position.

The ladies undergarment, according to the first form of the invention shown in Figs. 1 to 6, includes a bodice portion 10, which has its upper front part made so as to include, if desired, a brassière component or formation, and a skirt portion 11; the said bodice portion being also shown as having the conventional pair of shoulder straps 12.

These skirt and bodice portions are wholly separable, when not as above stated couplable as indicated in Figs. 1 and 2 and as perhaps most clearly shown, by a slide fastener 14 having the usual slide actuator 15 (see also Fig. 5).

A salient feature of the invention is the provision of such a slide fastener, preferably incidental to and by the aid of special constructions to be described below and with one of such constructions carried at the bottom of the bodice portion and with the other thereof an identical but a vertically reversed companion construction carried at the top of the skirt portion, for protectively housing the tapes and other parts of the slide fastener and in a manner relative to

these parts to afford a cushioning coaction therewith whereby the garment while being worn may be worn with perfect comfort yet ideal form fitting drape; and, in combination with the provisions just recited, a pair of specially shaped, specially placed and predeterminedly variously and individually dissimilarly stretchable elastic inserts, one of which, 16 is carried by the bodice portion 10, and the other of which, 17, is carried by the skirt portion 11.

The bottom of the insert 16 and the top of the insert 17 approximately align, at a fold line across the bottom of the insert 16 resulting from an inwardly turned-up hem 18 established by a stitching 19, and at a fold line across the top of the insert 17 resulting from an inwardly turned-down hem 20 established by a stitching 21; the stitching for attaching the sides of the insert 16 to the main back part of the bodice portion 10 being indicated at 22, and the stitching for attaching the sides and short bottom of the substantially triangular insert 17 to the main back part of the skirt portion 11 being indicated at 23.

These inserts are preferably of a ribbed elastic woven material, with substantially no stretch in a direction perpendicular to the waist line of the slip, but of such high stretchability in the direction of extension of said waist line that there is considerable stretch of the insert 16 in the direction of the arrow 26 and of the insert 17 in the direction of the arrow 27.

Thus, with, say, the slip made so as to be incut at the waist as shown in Fig. 1, any stretch needed for pull-over donning of the slip is provided for, as indicated in dot and dash lines in Fig. 1 at 28.

One of the already mentioned slide-fastener pocketing and cushioning constructions is provided at the bottom of the bodice portion 10, for the tape 32 of the slide fastener, and the other of said constructions is provided at the top of the skirt portion 11, for the tape 33 of said fastener. Said construction at the bottom of the bodice portion includes a turned-up inner bottom hem 34, and said construction at the top of the skirt portion includes a turned-down inner hem 35; each of these hems being established by a line of stitching 36, with said stitchings 36 also securing a pair of two-ply longitudinally folded facings 37 and 38 as best shown in Fig. 4. The fold along the facing 37 is lowermost, the fold along the facing 38 is uppermost, and the free edges of both plies of such folded facing are preferably pinked, as indicated at 37a and 38a.

The two constructions just described, for concealing and cushioning pocketing the tapes of the slide fastener and the parts carried thereby, extend, as will be observed from Fig. 6 when taken in connection with Fig. 5, all around the girth of the slip except for a distance slightly less than the width of the inserts 16 and 17 where they meet at, respectively, the bottom fold across the former and the top fold across the latter.

In the modification of the invention shown in Figs. 7 to 10, the construction of the undergarment is similar to that previously described and the bodice portion 10' is provided at the rear thereof with a horizontally stretchable elastic insert 16' which extends from the bottom to the top of the rear of the bodice portion 10'. The skirt portion 11' is likewise provided with a horizontally stretchable elastic insert 17' which ex-

tends downward into the top portion of the skirt portion 11' from the top edge thereof.

In addition, this modification of the invention includes means for releasably securing together the adjacent edges of the inserts 16' and 17' to prevent those adjacent edges from separating and forming an open gap at the rear of the garment when the wearer stoops over. This releasably securing means is so arranged as not to interfere with normal stretching of the adjacent edges of the inserts 16' and 17'.

The releasably securing means is characterized by the fact that the elastic insert 17' of the skirt portion 11' is formed with an upward extension 17a, clearly shown in Fig. 9, which overlaps the rear face of the bottom edge portion of the elastic insert 16' of the bodice portion 10'. Mounted along the inner face of the extension 17a there is a plurality of snap fastener elements 40 which are engageable with complementary snap fastener elements 41 mounted along the rear face of the bottom edge of the elastic insert 16'. The snap fastener elements 40 and 41 are independently mounted on small squares of cloth material 42 which are individually stitched to the adjacent faces of the elastic inserts 16' and 17' by stitches 43, as clearly shown in Fig. 10. The use of individual cloth squares serves to adequately mount the fastener elements 40 and 41 in position on the overlapped edge portions of the elastic inserts while at the same time having only a slight restraining effect on the stretching of those overlapped edge portions.

In other respects this form of the invention is similar to that previously described and like reference numerals identify like parts in each of the several views.

While the elastic inserts have been illustrated as applied only to the center of the back portion of the bodice and the skirt of the undergarment, this is by way of example only as the number of inserts may be increased as desired and they may be equally spaced about the circumference of the meeting edges of the garment portions without departing from the scope of the present invention.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means being continuously extended all around the garment except for a distance substantially equal to the width of said inserts at their adjacent ends, said inserts being located between the adjacent ends 70 of said connecting means, the garment being relatively non-stretchable in the direction of extension of said connecting means all the way along the length of the latter.
2. A garment of the kind described, comprising 75 separate bodice and skirt portions, means for

detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means being continuously extended all around the garment except for a distance substantially equal to the width of said inserts at their adjacent ends, said inserts being located between the adjacent ends of said connecting means, the garment being relatively non-stretchable in the direction of extension of said connecting means all the way along the length of the latter, said inserts at their adjacent ends being of substantially the same width.

3. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means being continuously extended all around the garment except for a distance substantially equal to the width of said inserts at their adjacent ends, said inserts being located between the adjacent ends of said connecting means, the garment being relatively non-stretchable in the direction of extension of said connecting means all the way along the length of the latter, said inserts at their adjacent ends being of substantially the same width and the second-named insert tapering downwardly toward its bottom.

4. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means being continuously extended all around the garment except for a distance substantially equal to the width of said inserts at their adjacent ends, said inserts being located between the adjacent ends of said connecting means, the garment being relatively non-stretchable in the direction of extension of said connecting means all the way along the length of the latter, said inserts at their adjacent ends being of substantially the same width and the second-named insert tapering downwardly toward its bottom, said inserts being at the rear of the garment.

5. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means being continuously extended all around the garment except for a distance substantially equal to the width of said inserts at their adjacent ends, said inserts being located between the adjacent ends of said connecting means, the garment being relatively non-stretchable in the direction of extension of said connecting means all the way along the length of the latter, said inserts at

their adjacent ends being of substantially the same width and the second-named insert tapering downwardly toward its bottom, said inserts being at the rear of the garment and substantially centrally of the rear.

6. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means extending all around the garment except for a distance substantially equal to the width of said inserts at their adjacent ends, the garment being relatively non-stretchable in the direction of extension of said connecting means all the way along the length of the latter, said connecting means being a single slide fastener of a length approximately equal to said distance.

7. A garment of the kind described, comprising separate bodice and skirt portions, means for detachably connecting said portions along a line girthwise extending relative the garment, and elastic inserts at the waist region of the garment, one such insert at the lower part of the bodice portion and the other at the upper part of the skirt portion, said inserts being arranged one above the other, and said connecting means extending all around the garment except for a distance substantially equal to the width of said inserts at their adjacent ends, the garment being relatively non-stretchable in the direction of extension of said connecting means all the way along the length of the latter, said connecting means being a single slide fastener of a length approximately equal to said distance, and there being a shielding and cushioning means for the tapes of said fastener and the parts carried thereby, and comprising plural-ply structures, one at the bottom of the bodice portion and the other at the top of the skirt portion.

8. A garment of the kind described, comprising separate bodice and skirt portions of non-elastic material, means for detachably connecting said portions along a line girthwise extending relative the garment, elastic inserts at the waist region of the garment, one such insert at the lower part of the bodice portion and the other at the upper part of the skirt portion, said inserts being arranged one above the other, said connecting means being continuously extended all around the garment except for a distance substantially equal to the width of said inserts at their adjacent ends, said inserts being located between the adjacent ends of said connecting means, and means for releasably securing together the adjacent edges of said elastic inserts without interfering with normal stretching thereof.

9. A garment of the kind described, comprising separate bodice and skirt portions of non-elastic material, means for detachably connecting said portions along a line girthwise extending relative the garment, elastic inserts at the waist region of the garment, one such insert at the lower part of the bodice portion and the other at the upper part of the skirt portion, said inserts being arranged one above the other, said connecting means being continuously extended all around the garment except for a distance substantially equal to the width of said inserts at their adjacent ends, said inserts being located

between the adjacent ends of said connecting means, and means for releasably securing together the adjacent edges of said elastic inserts without interfering with normal stretching thereof, said releasable securing means comprising an extension formed on one of said elastic inserts and overlapping the adjacent edge of the other of said inserts, and complementary snap fastener elements mounted on the adjacent faces of said extension and the said other insert, said snap fastener elements being mounted on separate squares of cloth material independently secured in position on said extension and said other insert.
